ELECTRIC LAMP SWITCH

Louis H. Morin, Bronx, N. Y., assignor to Rotolite
Device Co., Inc., New York, N. Y., a corporation
of New York

Application April 23, 1952, Serial No. 283,917

2 Claims. (Cl. 240—123)

1

This invention relates to lamp constructions. More particularly, the invention deals with a lamp having, as part of the lamp structure, means for actuating a switch mechanism in the bodily rotation or oscillation of the lamp to control igniting and turning-off of the lamp or in controlling a series of circuits or filaments of a circuit. Still more particularly, the invention deals with a lamp structure, wherein the column or lamp stem is utilized as the switching or circuit controlling member or medium of the lamp.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a sectional view through the lower portion and part of the upper portion of a lamp made according to my invention.

Fig. 2 is a bottom plan view of the structure with part of the construction shown in section and with part broken away.

Fig. 3 is a view similar to Fig. 2 showing another adaptation of my invention.

Fig. 4 is a view similar to Fig. 2 showing a complete base of modified construction and also diagrammatically illustrating the circuit to an electric bulb; and

Fig. 5 is a partial section on the line 5—5 of Fig. 4.

In lamp constructions of the type and kind normally used, the bulb, or bulbs, of the lamp are usually controlled by pull chains, rotary switches or push switches disposed in the upper portion of the lamp or, in other words, in close proximity to the bulb or the socket in which the bulb is mounted. With this type of construction, it has always been essential to reach in under a lamp shade to feel around in the effort to locate and then successfully operate the switch, particularly with the push-type of switches and rotary-type of switches. This has been further inconvenient from the standpoint that quite often a person, while seated in a chair, desires to change the amount of light from a lamp to increase or decrease the wattage and, in order to accomplish this operation, it has been necessary to rise from the chair to perform the operation.

The purpose of my invention is to construct what I term a switch lamp, wherein a body portion of the lamp itself, such for example as the column or stem, can be utilized as the switching member, element or medium and simply given a

2

rotary or rotary oscillatory motion to control the ignition of the bulb or bulbs or the filament in a multi-filament bulb in operating from a shut-off to a fully on position and, further, whereby the lamp may be actuated so as to move from a high wattage to the next lower wattage rather than in following the normal procedure of actuating a switch from the high wattage stage to a completely shut-off stage and then to the desired stage of operation.

In Figs. 1 and 2 of the drawing, I have illustrated one adaptation of my invention, in which 10 represents a lamp base in which is arranged a supporting body 11. At 12 I have shown the column or upstanding tube which, according to my invention, becomes the switch member, element or medium controlling actuation of the switch mechanism which is employed. I have also indicated diagrammatically at 13 means for supporting a lamp shade of any type and kind around a lamp socket 14, the lower portion only of which is shown.

In the supporting body 11 is arranged a bushing 15 in which is rotatably mounted a tubular shaft 16, through which the circuit wires, not shown, from the socket 14 pass into and contact with the switch mechanism 18 supported on the body 11 within the base 10. The switch member 12 or column is fixed to the shaft 16 through a cap or plate 19 and another cap or plate 20 is in the upper end of the column to support the shade brackets 13. The upper end of the shaft is threaded, as seen at 21, to receive and support the bulb socket 14.

The lower portion of the shaft 16 has substantially a square key portion 22, to which is keyed a switch actuating member or cam 23 held in place by a nut and spring washer structure, as at 24, the latter also serving to maintain the assemblage of the lamp structure with the base 10 and the supporting body 11.

The cam 23 is generally of the contour seen in Fig. 2 of the drawing and includes a protruding cam portion 25 for actuating the button 26 of the switch 18, which, for illustrative purposes, can be a micro-switch, which requires a minimum amount of operation in control of the circuit. It will be understood, however, that in utilizing other types of switches, or simply a switch operating button as diagrammatically illustrated in Fig. 4, a greater cam surface is provided on the cam 23.

Secured to the body 11 are spaced stop pins 27 which limit oscillatory movement of the switch actuating cam 23 and also the movement of the

member 12 or any of the parts or mechanisms carried or supported thereby. In this connection, it might be well to point out that the lamp shade supporting brackets 13 can provide a fixed coupling with a lamp shade so that simple rotation of the shade will actuate the switch mechanism to control the circuit, as will be apparent.

The switch of the structure shown in Figs. 1 and 2 of the drawing will operate to control a single circuit to turn the circuit to a lamp on or off. This may control a single bulb, or a series of bulbs, arranged in a single circuit, or a circuit controlled from a single switch.

In Fig. 3 of the drawing, I have shown a slight modification of the structure shown in Figs. 1 and 2, wherein I have substituted for the cam 23 a switch actuating member or lever 28, having a limited motion between stop pins 27, similar to the pins 27, and the lever 28 is movable toward and from a switch button 26' of a switch 18', otherwise similar to the switch 18. Here again, a circuit, similar to the circuit of Figs. 1 and 2, is controlled.

Quite often, lamps of the type and kind under consideration employ a series of bulbs, or a bulb having a series of filaments, whereby a different degree of wattage can be attained through actuation of a switch mechanism. In Fig. 4 of the drawing, I have diagrammatically shown a modified form of switch construction, as well as switch actuating mechanism. In this figure, 16' represents the lower end portion of a shaft, similar to the shaft 16, and at 29 and 30 I have diagrammatically shown two switch devices having stationary contacts 31 and 32, respectively, and movable spring contacts 33 and 34, the latter being actuated by spring buttons 35 and 36 normally supported by the springs thereon in inoperative position and moved into operative position to close the circuit between 31 and 33 and 32 and 34 by a switch actuating member or cam 37. The cam 37 has two circumferentially short cam surfaces 38 and 39 and a somewhat longer cam surface 40, part of the latter being in diagrammatically opposed relationship with respect to 39.

The cam 37 has an extended control segment or plate portion 41 having, in the upper surface thereof, a series of spaced recesses 42, 43, 44 and 45, the latter recess being shown in section in Fig. 5 of the drawing. At 11' I have shown part of the supporting body of the lamp base and, in this body is arranged a sleeve 46 supporting a bearing ball 47, at its lower end, the ball being tensioned as by a spring 48 to engage the recesses 42-45 as the cam 37 is rotated.

The cam 37, or the plate portion 41 thereof, operates in conjunction with stop pins 49 and 50 checking movement of the cam in the limit of rotary travel in both directions.

Associated with the showing in Fig. 1 of the drawing, I have diagrammatically illustrated a lamp bulb 51 having, by way of illustration, a 50 watt filament at 52 and a 100 watt filament at 53. In this connection, it will be understood that the lamps vary in these combinations and, quite often, have the 100 and 200 filaments which provide the combination of 100, 200 and 300 wattage. In the wiring diagram illustrated, 54 designates the negative source of supply and 55 the positive source of supply, the latter extending to the casing terminal 56 of the bulb 51; whereas, 54 has branches 57 and 58 which extend to the fixed contacts 31 and 32 of the switches 29 and 30, respectively.

At 59 and 60 are shown two other terminals of the lamp 51, 59 being the center end terminal

and 60 the ring terminal in accordance with standard practices. At 61 is shown a wire extending from the terminal 59 to the switch 33 and, at 62, is shown a wire which extends from the terminal 60 to the contact 34.

From the foregoing, the operation of the lamp or the bulb 51 of the lamp will be understood, keeping in mind that the cam 37 or switch actuating member is fixed to the shaft 16 in the same manner as the cam 23 is fixed to the shaft 15. The cam 37 is shown in the off-position in Fig. 4. By rotating this cam in a clockwise direction, as shown in Fig. 4, the cam portion 38 will be brought into engagement with the switch actuating button 35 and closing the circuit between contacts 31 and 33, thus completing the circuit to the filament 52. In this operation, the cam 37 is momentarily held at rest by the ball 47 dropping into the recess 44. By continuing the rotation of the cam 37 in the same direction, the cam 40 is brought into engagement with the button 36 and the cam 39 has released the button 35, thus the circuit through 31 and 33 is broken and the circuit is completed between contacts 32 and 34, thus igniting the 100 watt filament 53. In this position of the cam 37, the ball 47 is in the socket 43. Upon continuing the rotary motion to the cam 37, the cam portion 39 is brought into engagement with the button 35, again completing the circuit through the contacts 31 and 33 and the cam 40 maintains the circuit closed through the contacts 32 and 34. In other words, both filaments 52 and 53 will be ignited, thus giving the 150 wattage in the example given. In this last position of the cam or switch actuating member 37, the ball 47 will be in the socket 42.

With my improved switch construction and, assuming that at a period of operation the lamp is set with the switches controlling the filament 53 giving a 100 watt light, the control or switch actuating member 37 can either be moved in an anti-clockwise direction to provide a 50 watt light or rotated in the clockwise direction to acquire the 150 watt light. The directions of rotation as herein noted are associated with the illustration in Fig. 4 of the drawing and are not indicative of the direction of rotation of the lamp when in actual use.

From a standpoint of description, the parts 23, 28 and 37 may be said to comprise switch operating members and the cam portions 25, 38, 39 and 40 can be referred to as switch actuating elements. In all cases, the members 23, 28 and 37 are in the form of thin plates.

Having fully described my invention, what I claim as new and desire to secure by Letters Patent is:

1. A lamp of the character described, comprising a base, a shaft rotatably mounted on and projecting above the base and having an end extending into the base, a switch actuating column secured to and enveloping the shaft above said base, the base forming the support for said lamp, a switch mounted wholly in and supported by the base in spaced relation to said shaft end, said switch having an inwardly extending actuating button and being in circuit with the light bulb of the lamp, a radially extending thin plate-like actuating member fixed to said end of the shaft and rotatable therewith, means on the base and directly cooperating with said member for checking rotary movement of the shaft and member in both directions, and means on said member in alignment with said button and adapt-

ed to actuate said button to control operation of the lamp.

2. A lamp having a multiple filament light bulb, said lamp comprising a base, a shaft rotatably mounted on and projecting above the base and having an end extending into the base, a switch actuating column secured to and enveloping the shaft above said base, the base forming the support for said lamp, a switch mounted wholly in and supported by the base in spaced relation to said shaft end, another switch mounted wholly in the base in spaced relation to the first named switch, both of said switches having inwardly extending actuating buttons, the switches being in circuit with the light bulb of the lamp, a radially extending thin plate-like switch operating member fixed to said end of the shaft and rotatable therewith, means on the base and directly cooperating with said member for checking rotary movement of the shaft and member in both directions, means on said member in alignment with both switch buttons and adapted to actuate said buttons to control operation of the lamp, said means on said member being arranged at circumferentially spaced in-

10

5

ervals in controlling, through actuation of both switches, the different filaments of the light bulb, and means in the base and on said member independent of said first named means checking rotary movement of the member to yieldably retain said member in different circuit controlling positions.
